(57)

CLAIM

The ornamental design for a cherry-shaped container, as shown and described.

DESCRIPTION

FIG. 1 is an isometric view of a cherry-shaped container showing my new design;

FIG. 2 is another isometric view thereof with the top portion open;

FIG. 3 is a top plan view thereof;

FIG. 4 is a bottom plan view thereof;

FIG. 5 is a front side elevational view thereof;

FIG. 6 is a rear side elevational view thereof;

FIG. 7 is a right side elevational view thereof; and,

FIG. 8 is a left side elevational view thereof.
